[57] **CLAIM**

An ornamental design for a combined key ring and remote transmitter, as shown and described.

DESCRIPTION

FIG. 1 is a perspective view of the combined key ring and remote control transmitter, shown retaining two keys, with the keys illustrated in phantom;

FIG. 2 is a top view of the combined key ring and remote control transmitter;

FIG. 3 is a bottom view of the combined key ring and remote control transmitter;

FIG. 4 is a right, side elevational view of the combined key ring and remote control transmitter, relative to the view point of FIG. 2;

FIG. 5 is a right, side elevational of the combined key ring and remote control transmitter, relative to the view point of FIG. 3;

FIG. 6 is a rear, elevational view of the combined key ring and remote control transmitter, relative to the view point of FIG. 2; and,

FIG. 7 is a front, elevational view of the combined key ring and remote transmitter, relative to the view point of FIG. 3.
